UNITED STATES PATENT OFFICE.

ARCHIBALD B. HUBARD, OF OGONTZ, PENNSYLVANIA, ASSIGNOR TO GLOBE TICKET COMPANY, OF PHILADELPHIA, PENNSYLVANIA, A CORPORATION OF PENNSYLVANIA.

STRIP-FEEDING MECHANISM.

Application filed July 26, 1923. Serial No. 653,904.

To all whom it may concern:

Be it known that I, ARCHIBALD B. HUBARD, a citizen of the United States, residing at Ogontz, county of Montgomery, 5 and State of Pennsylvania, have invented a new and useful Improvement in Strip-Feeding Mechanism, of which the following is a full, clear, and exact description, reference being had to the accompanying drawings, which form a part of this specification.

In taximeters, it is desirable to provide a strip of duplicate tickets and print upon them, one at a time, certain data, particularly distances and rate of fare, and severally 15 the thus printed sheets, one at a time, and deliver them to customers as receipts. The tickets of the roll, as supplied to the taxicab, have certain uniform data printed upon them, such as the name of the taxicab operating 20 company and the headings for the data that are specially printed on each ticket by the taximeter mechanism.

It is convenient and desirable that the strip of tickets associated with the taximeter should be fed from a roll and positioned so that the ticket in advance will be located at the precise point required to receive the data to be printed thereon. This necessitates that the strip of tickets shall be 25 advanced a predetermined distance, no more and no less, as otherwise the imprinting would not be positioned precisely in the limited space provided for it on the individual ticket. Although the margin of error may 30 be slight in the travel of one ticket or a few tickets, it would become serious or prohibitive in the travel of a considerable number of tickets.

It is rather obvious to provide perforations near the margins of the strips and have them engaged by sprocket wheels which will be arranged to turn so as to advance the tickets, at each operation, a distance equal to the width of a ticket (measuring lengthwise of the strip). It is not practicable, however, to print such strip tickets in the first instance; that is, it is not practicable to perforate the strips so that each ticket will contain precisely the 45 same number of perforations invariably arranged in precisely the same position relative to the printing. Unless this can be done, the printing by the taximeter mechanism will not be in precisely the narrow 50 blank space provided for it.

I have overcome the difficulty by printing a strip of unperforated tickets of uniform width (which presents no difficulties) and by associating with the taximeter mechanism by which the strip of tickets, preparatory to the operation of the printing and cutter devices associated with the taximeter, is advanced a predetermined and invariable distance with the same certainty of operation as if it were advanced by sprockets 60 engaging properly positioned rows of ori-

fices.

A preferred embodiment of the invention is shown in the drawings, in which—

Fig. 1 is a perspective view of a portion 70 of the ticket strip engaged by the feed rolls.

Fig. 2 is a face view of the feed rolls in their mountings.

Fig. 3 is a section on the line 3—3 of Fig. 2, showing an end view of the rolls and 75 their mountings.

Fig. 4 is an end view, on a smaller scale, showing the feed roll gearing and operating means therefor.

Fig. 5 is a detail view of one of the perforator discs.

The strip of paper or other fibrous material *a* is unwound from a supply roll (not shown) and advanced by means of a pair of feed rolls or cylinders to bring a ticket 80 with proper registry with the cutter and printing mechanism (not shown). The rolls are preferably of a length equal to the width of the strip. One of the feed rolls *b* is preferably of steel and is provided near 85 its ends with circumferential grooves *c*, *c*. The other feed roll is preferably of medium hard rubber and comprises a body section *d* and end heads *e*, *e* of the same diameter as the body. Confined between the end 90 heads and the body are perforators *f*, *f*, which are discs having peripheral teeth extending above the periphery of the roll and into the grooves *c*, *c*, but not sufficiently far thereinto to bottom in the grooves. The 95 axles of the feed rolls, to which the rolls proper are secured, are supported in the side frames *g*, *g*. The axle of the lower roll is supported in a stationary box, while the 100 axle of the upper roll is supported in boxes *h*, *h*, slidable vertically in guides on the frame. The boxes *h*, *h*, are held down by springs *i*, *i*, whose tension is adjustable by means of set screws *j*, *j*, whereby the upper 105 feed roll holds the strip *a* firmly between it 110

and the lower feed roll, so that on rotation of the rolls the strip *a* will be advanced as the rolls turn.

It is inadvisable to positively drive only one roll, and I have accordingly secured intermeshing pinions *k*, *k* to the axles, which pinions are rotated in unison by means of a large gear wheel *l*.

The large gear wheel *l* is turned manually by means of a lever *m*, loosely mounted on the axle of the wheel *l* and carrying a pawl *o* engaging a ratchet wheel *n* secured to the wheel *l*. A holding pawl *p* prevents the ratchet *n* and the wheel *l* from slipping back from the position to which they are turned. Stops *r* and *s* limit the movement of the lever. A spring *t* returns the lever *m* to its initial position. One of the stops *s* is shown as adjustable in order that the ratchet which will be turned the predetermined number of teeth required to give the feed rolls the amount of rotation required to advance the ticket strip *a* a distance equal to the width of a ticket.

Without the tooth and groove construction (*f* and *c*), there is little likelihood of slippage between the ticket strip and the feed rolls, but the perforators act in as positive a manner as if they engaged previously prepared holes in the paper. While the tips of the teeth *f* should extend into the grooves, they need not extend far enough to actually penetrate the paper (although it is preferable to penetrate them lightly), and they should not extend far enough to bottom in the grooves. The teeth are, therefore, subject to no appreciable wear.

While I have described the invention as applied to taximeter mechanism, it is obvious that the invention is not limited to such use, but is applicable to any situation wherein it is necessary that a strip of paper or other fibrous material shall be moved step by step predetermined equal distances, especially where such feed mechanism is to coordinate with cutting or printing mechanism.

Having now fully described my invention, what I claim and desire to protect by Letters Patent is:

1. Strip feeding means comprising two feed rolls between which the strip is confined, means yieldingly pressing the rolls toward each other to increase the gripping of the strip by the rolls, means by which the rolls are turnable at equal peripheral speeds, one of the rolls having a circumferential groove, and a strip feeder having a series of perforating teeth fixedly carried by the other roll and projecting beyond the periphery of said roll and registering with and projecting into said groove of the other roll, whereby the paper is perforated in a continuous manner as it is fed by the rolls, said teeth being so close to each other that at least one of the teeth will be in engagement with the portion of the strip between the rolls. 70

2. Strip feeding means comprising two co-acting rolls for feeding the strip, gearing connecting said rolls, means for holding the rolls in feeding relation to the strip, there being a circumferential groove in one of the rolls and a wheel fixedly carried by the other roll and having spaced perforating teeth extending beyond the periphery of said roll into the groove in the other roll, the teeth on said roll being so close to each other that at least one of said teeth is in engagement with the portion of the strip between the rolls. 75

3. Strip feeding means comprising two co-acting rolls for feeding the strip, gearing connecting said rolls, means for holding the rolls in feeding relation to the strip, there being two circumferential grooves in one of the rolls, the other roll having an intermediate section, two end sections and a perforating toothed section between each end section and the intermediate section, the teeth on the last mentioned sections extending beyond the peripheries of the other sections into the grooves in the first roll, the teeth on said wheels being so close to each other, that at least one of said teeth is in engagement with the portion of the strip between the rolls. 80

In testimony of which invention, I have hereunto set my hand, at Philadelphia, Pa., on this 25th day of July, 1923. 85

ARCHIBALD B. HUBARD.
